TIMING DEVICE

Thomas R. Spalding, Chagrin Falls, Ohio, assignor to The K-W Ignition Corporation, Cleveland, Ohio, a corporation of Ohio

Application July 8, 1938, Serial No. 218,127

4 Claims. (Cl. 175—320)

The present invention relates to timing devices for periodically operating an electric circuit or circuits, either to make or interrupt the same.

The principal object of the present invention is the provision of a novel and improved timing device of the character referred to, simple in construction, reliable and stable in operation, low in current consumption, and operable in any position.

10 The invention resides in certain novel details of construction, combinations and arrangements of parts, and further objects and advantages of the invention will be apparent to those skilled in the art to which the invention relates from the following description of the preferred embodiment thereof, described with reference to the accompanying drawing forming a part of the specification.

Fig. 1 of the drawing shows a device embodying the present invention used to periodically complete one circuit and periodically interrupt another circuit for a predetermined interval of time.

Fig. 2 is an enlarged view of a portion of Fig. 1 with parts broken away to show the means of adjusting the vibrating contacts.

Referring to the drawing, the relay designated generally by the reference character A is of conventional construction comprising an operating coil 10 wound about a core 11 and a pair of normally open spring contacts 12 and 13, the right-hand ends of which contact members are insulated from but fixed to a bracket 14 formed integral with or fixed to a frame member 15, in any convenient manner. The contacts 12 and 13 are adapted to be closed upon energization of the operating coil 10 through the medium of an armature 16 pivotally connected adjacent its right-hand end to the frame 15 by members 17. 40 The armature 16 is continuously urged in a clockwise direction by a tension spring 18 connected to the right-hand end of the armature and to a projection 19 on the frame 15. Movement of the armature 16 under the action of the spring 18 is limited by a stop member 20 fixed to the free end of the armature and adapted to engage underneath a projection on the operating coil 10. The free end of the armature 16 is also provided with an angular member 21, made of insulating material, fixed thereto and provided with a small aperture 22 through which the free end of the contact 12 projects. The construction is such that when the armature is drawn towards the core 11 the upper contact 12 engages

the lower contact 13 completing an electric circuit hereinafter referred to.

The right-hand relay, designated generally by the reference character B, comprises an operating coil 25 wound about a core 26 and a pair of normally closed spring contacts 27 and 28 located in operative relation to the core 26. The lower contact 27 is carried on or fixed to the free end of a spring arm or reed member 29, the left-hand end of which is fixed to a bracket 30 supported on an insulating member 31 fixed to the upper end of the operating coil 25 in any suitable manner. A member 32 fixed to the underside of the free end of the spring member 29 serves as an armature. The upper contact 28 is carried by the free end of a spring arm or reed member comprising an upper member 34 made of relatively thin resilient material and having a curved portion 35 the left-hand end of which is connected to a resilient member 36 having less spring tension than the member 35. The member 36 is connected about midway between its ends to a member 37 which forms a support therefor. The right-hand end of the member 36 projects underneath the free end of the portion 35 for a purpose hereinafter referred to. The member 37 is carried by the member 31 previously referred to through the medium of a bracket 38.

The normally open contacts 12 and 13 of relay A are connected in series with a source of electrical energy, in the present instance a battery 40, and with the operating coil 25 of relay B, and the normally closed contacts 27 and 28 of relay B are connected in series with the battery 40, a manually controlled contact switch 41, and the operating coil 10 of relay A. When the switch 41 is closed, the operating circuit for relay A is completed from the battery 40 through line 52, switch 41, line 53, operating solenoid 10, line 54, spring arm 28, lower contact 27, upper contact 28, spring arms 34 and 36, members 37 and 33, and line 55 back to the opposite side of the battery 40 operating relay A to close the contacts 12 and 13, completing the operating circuit for the relay B, whereupon the armature 32 and the lower contact 27 of the relay B are drawn toward the core 26 and the spring arm or reed 29 which carries the same flexed. As soon as the contacts 27 and 28 part, the operating circuit for relay A is interrupted, permitting the normally open contacts 12 and 13 associated therewith to open, thus interrupting the operating circuit for relay B which, in turn, releases the spring member or reed 29 carrying the lower contact 27 of the normally closed contacts of relay B. When the ar-

mature 32 and the lower contact 27 are released from the core 26 they spring upwardly, and the contact 27 strikes the upper contact 28. Thereafter the contacts vibrate or bounce for an interval of time depending upon the characteristics of the spring arms 29 and 34 etc. The right-hand end of the spring member 36 which projects underneath the free end of the spring member 34 prevents the upper spring member from damping the vibration of the lower spring or reed member.

The frequency of the oscillations of the current in the operating circuit of relay A increases as the amplitude of the spring members decreases and the characteristics of the operating circuit of relay A are such that the relay will not respond to the closing of the contacts 27 and 28 of relay B until the frequency of the oscillations of the current in the operating circuit thereof reaches a predetermined amount depending upon the characteristics of the circuit. In other words the operating circuit for relay A will not be re-established until the contacts have almost stopped vibrating or bouncing. In the embodiment of the invention shown this condition is brought about by means of a resistance 42 and a condenser 43 connected in series circuit with each other and in parallel circuit with the operating coil 10 of relay A. Preferably, provision is made for varying either the resistance or the condenser, in the present embodiment the resistance 42, so that the characteristics of the circuit may be changed, or the circuit tuned, and, in turn, the interval of time that the circuit to the relay B remains open adjusted. A variable condenser and a fixed resistance may be employed in place of the fixed condenser and variable resistance shown, if desired. If adjustment or variation of the time interval is not desired a fixed resistance and a fixed condenser or some equivalent arrangement may be employed. In order to further stabilize the operation of relay A a high resistance 44 is connected in shunt circuit with the normally closed contacts of relay B.

The high resistance 44 connected in shunt circuit across the contacts of relay B and in turn across the operating circuit of relay A, causes a small amount of current to flow through the operating coil of relay A even though the contacts of relay B are open. This continuous current flowing through the operating coil of relay A causes the operating coil of relay A to maintain the contacts of said relay closed longer than would be the case in the event this current was not present. This has a stabilizing effect on the relay in that there is less variation in the length of time that the contacts of relay A are closed, than would otherwise be the case. Without this stabilizing current, the operation of the relay A insofar as the length of time that the contacts thereof are opened and closed, is more or less erratic but by increasing the period of time that the contacts are closed decreases the variation mentioned and stabilizes the mechanical operation of the relay.

The interval of time that the circuit to the relay B is maintained open may also be varied by changing the characteristics of one or both of the spring or reed members 29 and 34. In the embodiment of the invention shown, provision is made for damping the vibrations of the upper reed member 34 through the medium of a screw 45 adjustably threaded into a member 46 carried by the bracket 48 and located above the curved

portion 35. The period of vibration of the reed member 34 may be shortened by turning the screw 45 in a right-hand direction thus projecting the end thereof further from the member 46 and into closer proximity to the reed member. It will be understood that means other than that shown may be made for varying the characteristics of the reed member, and in turn the period of vibration of the member.

From the foregoing it will be apparent that the operating circuit for the relay B will be periodically opened or deenergized for a predetermined interval of time by virtue of the fact that periodically the relay A is rendered inoperative for a time interval. The fact that the operating circuit to relay B is periodically deenergized for a predetermined time interval, which interval may be varied in the preferred embodiment shown, can be taken advantage of to control an auxiliary circuit or circuits in various ways. As shown an auxiliary relay 47 is connected in series with the contacts 12 and 13 of relay A. This relay 47 is energized simultaneously with relay B and is provided with a plurality of contacts 48 and 49, the upper of which controls a normally open circuit 50 while the lower contact 49 controls a normally closed circuit 51. It will be readily apparent that the auxiliary relay 47 may be omitted and an auxiliary circuit controlled through the medium of additional contacts controlled directly by the relay A, etc. The fact that the operating circuit of relay B is periodically energized can also be taken advantage of in a plurality of different ways to control an auxiliary circuit or circuits. However, any additional relay or the like placed in the operating circuit of relay B will have an effect on the characteristics of the circuit and must be compensated for.

While the preferred embodiment of the invention has been illustrated and described with considerable detail, the invention is not limited to the particular construction and arrangement shown which may be varied within the scope of the invention and it is my intention to hereby cover all adaptations, modifications and arrangements thereof that come within the practice of those skilled in the art to which the invention relates.

Having thus described my invention I claim:

1. In combination a pair of relays, means for causing the operation of one of said relays to complete an operating circuit for the second of said relays, means for causing the operation of the second of said relays to interrupt the operating circuit for the first of said relays, and means for preventing the subsequent operation of the first of said relays for an interval of time, said last mentioned means comprising a pair of normally closed contacts carried by reed members and operatively associated with the second of said relays.

2. In combination a pair of relays, means for causing the operation of one of said relays to complete an operating circuit for the second of said relays, means for causing the operation of the second of said relays to interrupt the operating circuit for the first of said relays, and means for preventing the subsequent operation of the first of said relays for an interval of time, said means comprising a pair of normally closed contacts carried by reed members operatively associated with the second of said relays and adapted to vibrate when the operating circuit to said second relay is interrupted, the characteristics of the operating circuit of said first relay being such

that the relay is non-responsive for a period of time while said normally closed contacts are vibrating.

3. In combination of a pair of relays, a pair of normally open contacts operatively associated with the first of said relays and connected in series with the operating circuit of the second of said relays, a pair of normally closed contacts operatively associated with the second of said relays and connected in series in the operating circuit of the first of said relays, a resistor in shunt connection with said normally closed contacts, said normally closed contacts being carried on reed members adapted to vibrate when the operating circuit to the second relay is interrupted, the characteristics of the operating circuit of the first relay being such that said relay is inoperative for a period of time while said normally closed contacts are vibrating, and means for varying the characteristics of the operating circuit of the first relay.

4. In combination a pair of relays, a pair of normally open contacts operatively associated with the first of said relays and connected in series with the operating circuit of the second of said relays, a pair of normally closed contacts operatively associated with the second of said relays and connected in series in the operating circuit of the first of said relays, a resistor in shunt connection with said normally closed contacts, said normally closed contacts being carried on reed members adapted to vibrate when the operating circuit to the second relay is interrupted, the characteristics of the operating circuit of the first relay being such that said relay is inoperative for a period of time while said normally closed contacts are vibrating, means for changing the period of vibration of one of said reed members, and means for varying the characteristics of the operating circuit of the first relay. 5 10 15 20
